UNITED STATES PATENT OFFICE.

WALTER P. KAIN, OF BRIDGETON, NEW JERSEY, ASSIGNOR OF ONE-EIGHTH TO WILLIAM W. MORGAN, ONE-EIGHTH TO JOSEPH B. SHARP, AND ONE-FOURTH TO CLAYTON E. WOODRUFF, ALL OF BRIDGETON, NEW JERSEY.

UNIVERSAL BOTTLE AND JAR CLOSURE.

No. 894,153.

Specification of Letters Patent.

Patented July 21, 1908.

Application filed December 18, 1907. Serial No. 406,999.

To all whom it may concern:

Be it known that I, WALTER P. KAIN, a citizen of the United States, residing at Bridgeton, county of Cumberland, and State 5 of New Jersey, have invented a certain new and useful Improvement in Universal Bottle and Jar Closures, of which the following is a specification.

My invention relates to a new and useful 10 improvement in bottle and jar closures of that particular class in which a metal cap having a lining of packing material, such as cork, is fastened upon or over the mouth of the bottle or jar, and has for its object to 15 provide an exceedingly simple and effective device of this character by means of which a bottle stopper may be applied to and removed from the vessel without the use of machinery or special tools, but by simple 20 hand manipulation.

A further object of my invention is to provide a construction of stopper whereby the cap having been once removed from the receptacle can be replaced by hand as many 25 times as desired and obtain a seal as perfect as the original.

With these ends in view, this invention consists in the details of construction and combination of elements hereinafter set 30 forth and then specifically designated by the claims.

In order that those skilled in the art to which this invention appertains may understand how to make and use the same, I will 35 describe its construction in detail, referring by letter to the accompanying drawing forming a part of this specification, in which—

Figure 1 is a longitudinal section of my improvement applied to a bottle. Fig. 2, a 40 side elevation thereof, and Fig. 3, a plan view thereof.

In carrying out my invention as here embodied, A represents a disk portion having an annular corrugated depending flange 45 B, the lower edge of which is necked in as indicated at B' so as to engage the usual incline shoulder E on the external surface of the mouth of the bottle, thus forming an inverted cup in which is placed a concave-convex compression disk C having a conical indentation C' formed in the center thereof for engaging with a like indentation A' formed in the center of the disk A. After

the compression disk is placed within the inverted cup a disk D of cork or other packing material is also placed therein. By means of the conical indentations the cup proper is allowed to freely move when in position on the bottle or jar without disturbing the contact of the packing material, and to 60 also adapt itself to any irregularities of the lip or mouth of the vessel.

The merit of the construction herein described resides in the fact that the closures may be placed on a bottle or jar without the 65 use of a machine, thus they can be used to advantage on druggists prescription bottles, and by using rubber as the packing material they may be used on acids, or paraffined blotter paper on salts and baby foods, and 70 when the cap has been removed and only part of the contents used from the bottle the cap may be replaced and form as tight a seal as when first placed upon the bottle, due to the continuous spring action exerted by the 75 compression disk.

While I have shown the closure as being corrugated in order that a certain amount of spring action may be given to its flange to spring over the head upon the mouth of the 80 bottle and adapt itself to any variation in diameter of lip, it is obvious that these corrugations may be omitted, the closure being made of such material as will spring over 85 said head, by first engaging one side of closure and pressing other side in place with finger.

Having thus fully described my invention, what I claim as new and useful is—

A bottle or jar closure comprising a disk 90 having an annular corrugated depending flange, the lower portion of which is necked in, said disk having a conical indentation formed therein, a compression disk having a conical indentation formed therein for engagement with the first named depression, and a packing material, as and for the purpose set forth.

In testimony whereof, I have hereunto affixed my signature in the presence of two 100 subscribing witnesses.

WALTER P. KAIN.
